INVENTOR.

Edgar L. Logee

United States Patent Office.

EDGAR L. LOGEE, OF CENTRAL FALLS, RHODE ISLAND.

Letters Patent No. 101,285, dated March 29, 1870.

IMPROVED WINDOW-GUARD AGAINST FLIES AND MOSQUITOES.

The Schedule referred to in these Letters Patent and making part of the same.

To all whom it may concern:

Be it known that I, EDGAR L. LOGEE, of Central Falls, in the county of Providence and State of Rhode Island, have invented a new and improved Device for Keeping Out Flies and Mosquitoes; and I hereby declare that the following specification, taken in connection with the drawings, making a part of the same, is a full, clear, and exact description thereof.

Figure 1 is a view of the window from inside.

Figure 2 is a vertical section showing the window partially open.

The object of my invention is to produce a self-adjusting device, which when applied to a window shall render that space between the two sashes which is made by the raising of the one or the dropping of the other sufficiently tight to prevent the ingress of flies or mosquitoes.

The glass, being set into the sash and not parallel with the outside of the same, there will be no open space between the top part of the lower sash and the lower part of the top sash while they remain in contact with each other, which they do when the window remains closed; but if either sash be opened so that the contact is no longer preserved an open space will be left equal in width to the distance of the glass from the outside of the sash.

It is now almost a universal custom during the warm season to keep the windows open except in stormy weather, and to place within the open space a netting of wire or other material to keep out the flies and mosquitoes, which in many localities are very numerous, and in nearly all are attracted to the house during the evening by artificial light. These insects finding their way through the open space effectually checked by the netting, make use of the space between the sashes already described.

My invention is attached to the under side of the upper sash, as shown in fig. 1, by the metal end pieces, which are so constructed as to also act as guides to the horizontal lip A, which, being cut out to receive the perpendicular part of the sash B, shuts tightly against the glass, and is held in that position by springs C C' upon each end of the same.

The space now left between the lip A and the upper sash is closed by a strip, E, attached to the lip A, or both may be made in the same piece.

The operation of my invention is as follows:

The springs press the lip A against the glass, but not with sufficient force to prevent the sliding of either sash.

In order, however, to have the free use of the window it is oftentimes necessary to force back the lip A, which slides between the guides x and x' to allow the horizontal piece F to pass it.

For this purpose I place upon the inside edge of the lip A two half-circular pieces of metal, H and H', which being acted upon by the piece F pushes back the lip A until it has passed them, when the lip is again pressed against the glass by the action of the springs.

What I claim as my invention, and desire to secure by Letters Patent, is—

The device herein described for closing the space between the upper and lower sashes of a window for the purposes specified, consisting in the combination and arrangement of the lips A and E, the springs C and C', the guides x and x', and the curved rods H and H', in the manner substantially as set forth.

EDGAR L. LOGEE.
